United States Patent Office.

A. M. CULVER, OF BEDFORD, OHIO.

Letters Patent No. 63,222, dated March 26, 1867.

IMPROVEMENT IN COMBINED SHEEP-HOLDER AND WOOL-TYER.

The Schedule referred to in these Letters Patent and making part of the same.

TO ALL WHOM IT MAY CONCERN:

Be it known that I, A. M. CULVER, of Bedford, in the county of Cuyahoga, and State of Ohio, have invented certain new and useful improvements in Combined Sheep-Holders, Wool-Tyers, &c.; and I do hereby declare that the following is a full and complete description thereof, reference being had to the accompanying drawings, making a part of this specification, in which—

Figure 1 is a side view of the machine.

Figure 2 is an end view.

Figure 3 is a top view of the same.

Figures 4 and 5 are detached sections, to which reference will be made.

Like letters refer to like parts in the different views.

This machine consists of a shearing-table and wool-folder combined with an appliance for holding the sheep while being shorn. A A and B B, fig. 1, are the legs of the table, which are so connected to the tops C, fig. 3, as to permit of their being folded up for a purpose hereafter shown. D D are a pair of adjustable arms, which are pivoted to the legs A at the points E, and to each other at the ends F. On the outer ends of the arms are secured the upright stays G G'. It will be observed that G' is longest, and through which is projected the horizontal bar H, which is allowed to slide backward and forward through the stays for a purpose hereafter described. I is a lever, the lower end of which drops into the notches cut into the upper side of the bar H. J is a shackle, so fitted to the inner end of the bar as to allow it to turn or revolve. The opposite stay G is provided with a similar shackle, arranged in the same way and for the same purpose. It will be seen that these shackles, &c., are at each end of the shearing-table C' upon which the sheep is laid for shearing. The top of the machine used as the fleece-folder is constructed in three sections, C K L, fig. 4. K, the central section, is fixed to the form and legs as shown in fig. 3, and is covered with a strap of leather, K', which is fastened to the table at the point X. The strap extending either way from this point is loose, so that it can be lifted from the table, as will hereafter be shown. The outside sections of the top C L are so hinged to the middle section that they can be turned upward to the position shown in fig. 4, thus making a kind of open box.

The manner of using this apparatus is as follows: The sheep is placed upon the table C'; its legs are then stretched out and secured to the shackles referred to by passing a foot through the rounded notches a, and then securing it by slipping the slides b over them, thus preventing the foot from being drawn out by the struggles of the animal, and which is also kept extended by the lever falling into the notches in the bar H, which may be lengthened or shortened according to the length of the animal. The sheep, on being properly secured, the fleece is then taken off and properly spread out and arranged upon the table or folder by doubling or folding over the sides of the fleece until it is of the width of section K; previously, however, the strings for tying the fleece are drawn through the holes e, fig. 3, and stretched along toward the front end of the table, over the edge of which they are allowed to drop for a short distance. The strings and fleece being thus arranged, the side sections are then turned up, as shown in fig. 4, and held in this position by the bar P, attached to the short or front end of the strap. This bar projects beyond the width of the strap far enough to pass through the holes R in the upturned sides of the table, and locks them together by a notch on the protruding ends. The fleece is then rolled partially up, and the long end of the strap is then brought over to the front and hooked to the lever S, fig. 5. The lever is then depressed, and this draws the strap forward, at the same time rolling or folding up the fleece until it reaches the bar P, to which the short end of the strap is secured, as aforesaid. This end of the strap answers the place of a solid head-block, against which the fleece is rolled in the ordinary wool-tying machine. When the fleece is thus rolled up, the lever is retained in its depressed position by the hook T until the wool is tied, which is done in the ordinary way, which being done, is then removed, and the operations of shearing and tying again repeated.

The purpose of having the shackles so as to turn upon the bar H is that the sheep may be turned from side to side or completely over, so as to adjust it to the convenience of the shearers. As above observed, the legs of this apparatus are so connected to each other and to the table that they can be easily disconnected and folded up under the top, and thus made convenient for transportation, or to be stored away for future use. The advantage of thus combining the two machines is the convenience of the wool-tying section of the apparatus to

the shearer, as the fleece rolls from the sheep directly on the folder, and thereby saves the time and care to take it from the shearer to the folder, which, when the fleece is light and torn, is a matter of no little trouble and inconvenience. By using the short end of the strap as a substitute for a head-block in the manner as above described, makes this part of the apparatus much more simple in construction, less expensive, and far more convenient than a fleece-holder constructed with a head-block in the ordinary manner.

What I claim as my invention, and desire to secure by Letters Patent, is—

1. The sides of the table C L, as arranged in combination with the strap K' and lever S, for the purpose and in the manner described.
2. The arrangement of the sides C L, and strap K, in combination with the table C', shackle J, bar H, and lever I, as and for the purpose herein set forth.

A. M. CULVER.
